UNITED STATES PATENT OFFICE.

EDWIN BURNHAM STORY, OF NORTH GRAFTON, MASSACHUSETTS.

FOLDING CASE.

1,076,076.

Specification of Letters Patent.

Patented Oct. 21, 1913.

Application filed July 20, 1912. Serial No. 710,552.

To all whom it may concern:

Be it known that I, EDWIN B. STORY, a citizen of the United States, residing at North Grafton, in the county of Worcester 5 and State of Massachusetts, have invented new and useful Improvements in Folding Cases, of which the following is a specification.

The object of the present invention is to 10 provide a folding case comprising two members adapted to telescope one into the other thereby forming a completely closed box. The structure may be built of paper or other light material and is so arranged that it 15 can be shipped in knock-down condition and subsequently assembled for use.

More particularly the invention aims to provide a structure wherein the inner receptacle is locked against accidental removal, 20 this locking being effected through the medium of a flexible handle carried on the inner receptacle and protruding through the housing member. A tongue on the housing member co-operates with this handle in limiting endwise movement of the inner receptacle. End flaps are provided on the inner receptacle to prevent spilling of its contents 25 after such endwise movement as is permitted before the tongue comes into engagement with the handle to form the locking means. The inner and outer members may each be constructed of a single paper blank so arranged that it can be flattened out 30 when not in use.

Referring to the accompanying drawings, Figure 1 is a perspective view of the complete case in condition for use. Fig. 2 is a perspective view of the inner section moved outwardly as far as the handle lock will 40 permit, a portion of the housing member being broken away to disclose the structure within. Fig. 3 is a detail of the handle lock illustrating the mode of unlocking. Fig. 4 is a plan of a fragment of the flat 45 blank out of which the housing member may be constructed, illustrating the irregular cut whereby the locking tongue is formed. Fig. 5 is a perspective view showing the inner member partly folded up.

The folding case of the present invention 50 comprises an outer or housing member 1 and an inner or containing receptacle 2. The housing member 1 may be constructed of paper or of fiber, leather or the like in 55 a single thickness or reinforced by a plurality of thicknesses as desired and is shaped

up out of a rectangular blank with overlapping ends at the bottom 3. This overlapping gives stiffness and rigidity to the bottom and is of value when the case is of large 60 size such for instance as might be used for laundry boxes, suit cases and the like. At the center of the blank out of which the housing member is formed is a U-shaped cut 4 of substantial width which leaves a 65 tongue 5 attached integral to the sheet and serviceable as a lock for the handle of the case as hereinafter explained. The inner member or receptacle may also be formed of a single sheet of paper or other suitable material reinforced or not as desired, the blank being cut to form a side wall 6, a top wall 7, a bottom wall 7', end walls 8 and 9 with extensions 10 and 11, and suitable wings 12 for engagement with slots 13 in the top and 70 bottom walls to lock the end walls in position. Fig. 5 shows the end wall 8 folded up and end wall 9 in position ready for folding. The end extensions 10 and 11 have the functions of stiffening the ends of the 75 receptacle to give rigidity to the entire structure and to prevent collapse of the top and bottom walls or crushing at the corners of the case. They have the additional and very 80 important function of preventing exposure 85 or spilling of the contents of the receptacle in case of the partial withdrawal of the inner receptacle from the housing member as illustrated in Fig. 2. This partial withdrawal may take place before the handle 90 lock comes into action. A flexible handle 14 has its ends tucked through slits in the upper wall 7 of the receptacle and is there pasted, riveted or otherwise secured in position to form a flexible loop. Preferably 95 this handle is constructed of cloth, tape or similar material, thin enough and flexible enough to offer no substantial resistance when the inner receptacle is being slipped into position within the housing member. 100 It will be understood that the inner receptacle fits snugly within the housing member.

The flexible tongue 5 with which the housing member is equipped can be tilted upward at a corner or can be otherwise adjusted as 105 indicated in Fig. 3 to allow the flexible handle to slip through. Once in that position, the tongue serves as an effective lock preventing inadvertent sliding motion of the inner receptacle and securely locking the 110 two parts together. Some slight longitudinal movement of the inner receptacle is

possible as indicated in Fig. 2 but the end extensions 10 and 11 so overlap the face of the inner receptacle that the case still remains intact.

5. The structure may be reinforced as desired but even in reinforced condition combines great strength and security with lightness, rigidity and freedom from collapse or sagging.

10. The cases may be built in any size desired even in sizes small enough for lunch boxes and the like.

What I claim as new and desire to secure by Letters Patent of the United States is:

15. 1. A knock-down paper box comprising a member having an opening in its uppermost side, said opening being U-shaped to form a tongue, another portion of said box having a flexible handle permanently attached thereto, said flexible handle being adapted for introduction from below so that the handle may be pulled up through said slot into useful position, said tongue coöperating with said handle to prevent accidental withdrawal of the handle through the opening.

20. 2. A knock-down case consisting of a housing member open at both ends and having a slot in its top, and a correspondingly shaped inner receptacle adapted to telescope into said housing member through an open end thereof, said members being each formed of a single blank and readily flattened out when not in use, said inner receptacle having a flexible handle adapted to project through 25 the slot in said housing member, said housing member having an integral tongue projecting into said slot to serve as a lock for said handle.

3. A knock-down paper box consisting of 40 a substantially rectangular housing member, said member being adapted to fold down flat for shipment, a correspondingly shaped inner receptacle adapted to telescope longitudinally into said housing member through 45 an open end thereof with a snug fit, said inner receptacle being formed of a single paper blank and capable of ready flattening when not in use, said inner receptacle comprising a side section, top and bottom sec-

tions, end sections and means for securing 50 the end sections in position and extensions for said end sections overlapping the front face of the inner receptacle, said inner receptacle carrying on its top section a thin flexible handle which may be in place on the receptacle when it slides into the housing member, said housing member having a slot through which said handle may be raised and a tongue carried by said housing member and projecting into said slot to serve as 60 a stop for limiting accidental endwise movement of said inner receptacle to a distance not exceeding the width of the end extensions.

4. A knock-down case consisting of a substantially rectangular housing member open at both ends, an inner receptacle adapted to telescope into said housing member with a snug fit, said inner receptacle having end extensions overlapping the front face of 70 said receptacle, a flexible handle carried by said inner receptacle, said housing member having an opening through which said handle may protrude, said opening being U-shaped to form a tongue coöperating with 75 said handle to prevent accidental displacement of the inner receptacle by a distance exceeding the width of said end extensions.

5. A knock-down case consisting of a substantially rectangular housing member open 80 at both ends, an inner receptacle adapted to telescope into said housing member with a snug fit, said inner receptacle being open along substantially all of one side, a U-shaped slot in said housing member forming 85 a tongue, and a flexible handle carried by said inner receptacle and adapted to protrude through said slot, said handle coöperating with said tongue to form a lock preventing accidental longitudinal displacement 90 of the inner receptacle.

In witness whereof, I hereunto subscribe my name to this specification in the presence of two witnesses.

EDWIN BURNHAM STORY.
